STOOL BASE STRUCTURE

Gwylm H. Bozarth, Kansas City, Mo., assignor to
 Fixtures Manufacturing Corporation, Kansas
 City, Mo.

Application March 28, 1949, Serial No. 83,799

2 Claims. (Cl. 155—134)

1

This invention relates to stools, particularly those commonly employed adjacent a counter or the like and has to do with the base structure thereof, irrespective of the precise nature of the stool or its use.

It is the primary object of this invention to provide a stool base structure having novel means of interconnecting the component parts thereof and joining the entire assembly rigidly to a floor or the like, all capable of quick and easy attachment or removal without the use of special tools or without the necessity of particular skill in the assembling operation.

It is the most important object of the present invention to provide stool structure having a base provided therein with means for rigidly securing the same to a floor that is easily accessible at the top thereof and having a vertical column removably secured thereto and provided with attaching means disposed exteriorly of the column, all to the end that the latter may be attached to the base as the last step of the assembling operation.

Other more minor objects will be made clear or become apparent as the following specification progresses, reference being had to the accompanying drawing, wherein:

Fig. 1 is a perspective view of a counter stool made in accordance with my present invention.

Fig. 2 is a vertical cross-sectional view taken on irregular line II—II of Fig. 1.

Fig. 3 is a transverse cross-sectional view taken on line III—III of Fig. 2; and

Fig. 4 is a cross-sectional view taken on line IV—IV of Fig. 2.

The stool forming the subject matter of this invention includes a hollow base 10, a vertical cylindrical column 12, a tripod 14 and a seat, broadly designated by the numeral 16.

The hollow base 10 is substantially frustoconical and has its greatest diameter next adjacent a floor or the like 18 upon which base 10 rests and is secured. A floor plate 20 resting directly upon floor 18 within the base 10 is disc-like and secured to floor 18 through the medium of a plurality of screws 22 or other fastening elements depending upon the construction of the floor 18.

Plate 20 has a centrally disposed offset portion 24 that is centrally perforated for receiving a vertical bolt 26 and formed to prevent rotation of polygonal head 28 of bolt 26. The top wall of the base 10 includes a cross-bar 30 and an annular up-turned flange 32. The cross-bar 30 has a central opening 34 for receiving the bolt 26

2

that extends a distance above plate 20 to receive a nut 36.

The outside diameter of the column 12 is substantially the same as the inside diameter of flange 32 to the end that the former rests directly upon shoulder 38 formed on base 10. A bearing plate 40 crosses the uppermost end of the column 12 and has an opening 42 formed therein for rotatably receiving a spindle 44 forming a part of the tripod 14.

A pair of elongated, vertical rods 46, disposed within the column 12, is threadably mounted or otherwise removably secured at the lowermost ends thereof within the cross-bar 30, there being one bar 46 on each side of the opening 34. The uppermost ends of the rods 46 pass through the bearing plate 40 and have nuts 48 thereon disposed exteriorly of the column 12.

Tripod 14 includes, in addition to the spindle 44, spider arms 50 that are in turn secured rigidly to the seat 16 in any conventional manner.

Seat 16 usually includes a pad 52 having a ring 54, the latter of which is provided with structure underlying the pad 52 for connection with the spider arms 50.

It is clear from the foregoing that in mounting the entire stool upon floor 18, the operator first affixes the plate 20 in the desired position by fastening screws 22 after first positioning bolt 26 to receive base 10. Base 10 is thereupon placed over the plate 20 and bolt 26 projects through the opening 34 of cross-bar 30 in the manner shown in Fig. 2. Since the uppermost end of bolt 26 is exposed and easily accessible, the operator can turn the nut 36 to draw base 10 tightly against floor 18.

The next step in the assembling operation is to affix the rods 46 into the cross-bar 30, whereupon column 12 is threaded over the rods 46 and disposed with its lowermost end resting upon shoulder 38.

The operator then places the bearing plate 40 in position over the rods 46 and applies nuts 48, both of which are exposed for easy access. When the nuts 48 are drawn tight, the column 12 will be held tightly against the shoulder 38 of the base 10. The tripod 14 affixed to the seat 16, may then be removably mounted within the opening 42 of bearing 40 for free rotation therein.

It is apparent that no special tools are needed for the assembling operation as above set forth, or for disassembling as desired. Furthermore, no particular skill is needed and the entire structure may be shipped in a knocked-down condition with only the simplest instructions concern-

ing mounting of the stool upon a floor or the like. Having thus described my invention, what I claim as new and desire to secure by Letters Patent is:

1. In a stool of the kind described, a hollow base having a top; a plate in the base having means of attachment to a floor; parts on said plate and extending through said top of the base for holding the latter against the floor; a column covering said top of the base and extending upwardly therefrom; a number of rods in the column, said rods being removably secured at the lowermost ends thereof to said top of the base; and means at the uppermost end of the rods for releasably holding the column against the base. 10

2. In a stool of the kind described, a base; means for removably securing said base to a floor; a column extending upwardly from said base; a number of rods in the column secured 20

at the lowermost ends thereof to said base; and means at the uppermost ends of the rods for holding the column secured to said base.

GWYLM H. BOZARTH.
